CLAIM

The ornamental design for a bicycle frame, as shown and described.

DESCRIPTION

FIG. 1 is a rear, top, and right side perspective view of a first embodiment of a bicycle frame embodying our new design; FIG. 2 is a right side elevation view thereof; FIG. 3 is a left side elevation view thereof; FIG. 4 is a rear elevation view thereof; FIG. 5 is a front elevation view thereof; FIG. 6 is a top plan view thereof; FIG. 7 is a bottom plan view thereof; FIG. 8 is a rear, top, and right side perspective view of a second embodiment of a bicycle frame embodying our new design; FIG. 9 is a right side elevation view thereof; FIG. 10 is a left side elevation view thereof; FIG. 11 is a rear elevation view thereof; FIG. 12 is a front elevation view thereof; FIG. 13 is a top plan view thereof; and, FIG. 14 is a bottom plan view thereof.

The broken lines in the drawings illustrate portions of the bicycle frame that form no part of the claimed design.

1 Claim, 10 Drawing Sheets
